ARTICULATED TRAY

Robert B. Greer, Los Angeles, Calif.

Application June 16, 1955, Serial No. 36,537

Term of patent 7 years

(Cl. D44—10)

Fig. 1 is a plan view of an articulated tray, in flat position, and showing my new design.

Fig. 2 is a cross-sectional view showing said tray in a converted position with the sides folded out of the plane of the bottom.

In Fig. 1, the tray is symmetrical on both major and minor axes, and in Fig. 2, the tray is symmetrical on the medial axis. The portions shown in full lines are continued around the entire tray.

I claim:

The ornamental design for an articulated tray, substantially as shown and described.
